Inventor
John E. Williams
Attorney

UNITED STATES PATENT OFFICE.

JOHN E. WILLIAMS, OF DULUTH, MINNESOTA.

AMPLIFYING HORN.

Application filed September 18, 1922. Serial No. 588,841.

To all whom it may concern:

Be it known that I, JOHN E. WILLIAMS, a citizen of the United States, residing at Duluth, in the county of St. Louis and

5 State of Minnesota, have invented certain new and useful Improvements in Amplifying Horns, of which the following is a specification, reference being had therein to the accompanying drawing.

10 My invention relates to sound amplifying horns, and has special reference to such a device for connection with phonographs or the like.

The principal object is to produce an improved form of horn which in operation 15 will render the sound transmitted therethrough more pleasing and distinct than heretofore experienced in the common form of such device.

20 The novel advantages of my present invention will appear evident in the further description thereof, though the same is obviously far from doing justice to the improvement as compared with the actual results accomplished.

25 In the accompanying drawing, forming part of this application and in which like reference characters indicate like parts:

Figure 1 is a perspective view of my improved amplifying horn, and

30 Figure 2 is a cross sectional view taken on the line 2—2, Figure 1.

Broadly considered, the invention simply embodies the incorporation of air chambers 35 upon opposite sides of the horn, intermediate of the ends thereof, said air chambers in the embodiment here illustrated occurring at 1—1, they being the full height of the side walls of the horn and any thickness desired, preferably with their end terminations converging into the side walls of the horn some distance from the extreme ends thereof so that both the external and in-

ternal lines of the horn are gracefully curved. The external walls of these chambers are indicated at 2, while the internal walls are indicated at 3.

45 Through the internal walls 3 are formed openings 4 which I prefer to make in the form of an Amati scroll, the same having been established as an ideal form of opening in chambers for similar purposes, as for example in various stringed instruments.

50 In the construction of this horn I prefer to use well seasoned spruce wood, the same being known to have exceptional qualities 55 for such.

A horn built in accordance with the above 60 description has proven capable of quite remarkable results in amplifying sound transmitted therethrough by sympathetic vibration.

Having thus described my invention, what I claim and desire to secure by Letters Patent, is:

65 A sound amplifying horn arcuate in side elevation and rectangular in cross section throughout comprising spaced primary side walls parallel for at least half their length and flaring outwardly arcuately for the remainder of their length, said walls having openings therethrough, and auxiliary side walls substantially straight throughout their entire length and extending from the extreme outer extremity of the primary walls 70 to a point adjacent the opposite ends of the primary walls and where the latter are parallel, the edges of all the side walls being securely attached to the top and bottom walls of the horn.

75 In testimony whereof I hereunto affix my signature in the presence of two witnesses.

JOHN E. WILLIAMS.

Witnesses:

S. C. BRONSON,
S. GEO. STEVENS.
